[57] ABSTRACT

A complete monolithic concrete structure having any desired architectural form and appearance is constructed in a series of operations wherein the foundation, the interior and exterior walls, and the roof are cast-in-place. The foundation and walls are sequentially formed by first temporarily interconnecting a plurality of relatively small concrete forms, after which moist concrete is allowed to cure within the forms. A temporary supporting structure is then erected to support the roof form. After the roof structure has cured, the temporary supporting structure is removed. The required electrical, plumbing, and reinforcing elements are embedded in the cast-in-place structures, and suitable framed openings are left in the wall structures to accept doors and windows.

METHOD FOR MAKING CAST-IN-PLACE CONCRETE STRUCTURES

BACKGROUND OF THE INVENTION

1. FIELD OF THE INVENTION

The present invention relates to a system for producing buildings, and more particularly, a method of making a monolithic cast-in-place house, building or like structure, wherein, in a series of steps, the foundation, walls and roof are formed. The system involves the construction of a foundation, a wall, and a roof, each of which is formed by temporarily interconnecting a series of relatively small lightweight concrete forms.

2. DESCRIPTION OF THE PRIOR ART

One of mankind's most pressing problems is the development of a system for producing low-cost housing capable of providing security against the adverse elements of weather, earthquake, fire and vermin. In conventional building systems of the present day, even the so-called prefabricated systems, use is made of thousands of individual pieces of many materials involving many separate processes and employing several skilled crafts and many skilled men. As a result, building construction, be it for a house, industrial building, warehouse, etc., is expensive, time-consuming, requires skilled labor, and in many cases requires the use of heavy construction equipment.

In spite of the limited success that has been achieved with prefabricated wood and other construction materials in adapting mass production techniques to the production of houses, most people still prefer a house made of masonry material. The reason for this is simple: concrete masonry is the strongest, most durable building material known to man, and is the cheapest material for effectively combatting the adverse effects of weather, earthquake, fire and vermin. However, known techniques for the construction of masonry houses have many of the same limitations as techniques for constructing frame or similar structures. More particularly, masonry houses made of brick require the individual laying of many bricks, stone or the like along with the construction of the structural members of the house, the plastering of the interior walls for appearance purposes, the laborious chiselling out of the windows and door frames, and the additional chiselling of the masonry materials for accommodating plumbing, electric and gas conduits. As a result, known techniques for forming a masonry house are expensive, time-consuming and require skilled craftsmen.

Faced with the alternative techniques mentioned above, the construction industry has long sought a system for creating a commercially acceptable built "in-place" house made of concrete material. To this end, the construction industry has attempted, without success, to develop a system of making a house by casting concrete. One technique involves the preliminary erection of a structural steel skeleton arrangement made of I-beams, followed by the placing of large slabs of concrete panels (which are pre-cast at a factory) between the beams. The concrete panels are usually very large, in order to minimize the cost of construction, and hence resort must be made to the use of heavy equipment to transport the panels and to position the panels between the I-beams. One of the primary disadvantages of this type of system is that the result of this technique is the completion of only the wall portions of

the building. Conventional building roof techniques must then be resorted to in order to complete the building. Hence, this construction technique has the disadvantages of requiring heavy equipment, involving piecemeal construction, and requiring a large capital investment in a factory for producing the pre-cast panel.

A second known technique involves the use of extremely large concrete forms, some large enough to complete major wall portions of a building structure. One obvious disadvantage of this system is the requirement for heavy equipment for transporting and positioning the forms. After the forms are in position, moist concrete is poured or cast-in-place at the site of the building structure. Besides the disadvantage attendant with the weight and bulk of the forms, which necessitates heavy construction equipment and thereby increases the cost of construction, this technique has the disadvantage of only being capable of producing one type or design of building. Also, as in the previously described prior art technique, the roof structure was often constructed using standard techniques which employed many different building materials, such as wood, structural members, planking or sheathing, and a conventional roofing material.

Another known technique for forming cast-in-place masonry buildings was to employ a plurality of individual forms which are temporarily secured together to form two spaced wall members providing a form for casting concrete. Often these individual forms were made of heavy metal which necessitated the use of construction equipment, with the forms being so constructed that only one design or type of structure could be made. Furthermore, the forms were employed for making the walls of the building, after which conventional techniques were employed for completing the structure. In addition, the appearance of the resulting wall was frequently unacceptable because of the joint lines formed in the concrete, and hence finishing of the wall (e.g., plastering) was often added as an additional step of construction; hence, the cost of construction was increased by the requirement for additional construction materials and skilled labor.

In summary, heretofore the construction industry has lacked a system of constructing a commercially acceptable built-in-place building structure of concrete.

Concrete is the most desirable construction material because it is the most inexpensive and readily available permanent building material, and it is fireproof, rot-proof vermin-proof, earthquake-proof, and weather-proof. Furthermore, concrete may be poured or cast in place. Prior systems for concrete masonry structures often required heavy construction equipment, additional finishing processes, and, most importantly, do not result in a low-cost, complete masonry structure. More particularly, thousands of attempts have been made by giants of the construction industry to perfect a commercially acceptable built-in-place house of concrete, and a system to produce the house, including such names as Thomas A. Edison (see U.S. Pat. No. 1,123,266, which issued on Jan. 5, 1915), and many, many others. None of these systems were successful as to commercial success, for the following primary reasons:

The appearance of the built-in-place concrete house produced with the previous systems were unacceptable because of many ugly imperfections of the concrete. In order to cure these defects, further finishing operations were required, thereby increasing the cost of construction. Furthermore, the prior art systems were difficult to erect and were incomplete, and this further reduced the economy of the cast-in-place concrete house. The system of the present invention has solved these problems by employing a concrete form which will economically produce beautiful designs and architectural results in the concrete. With the system of the present invention, no further finishing is required to the concrete surface.

The prior art systems required large forming surfaces which necessitated heavy, expensive machinery and were limited to a few plans or designs, etc. The system of the present invention goes together like a huge erector set, with no sections larger than one man can handle. The sections employed in the system of the present invention can be put together by unskilled men using mass production techniques. In addition, the innovative hardware used in the system of the present invention renders the system simplicity itself.

The system of the present invention is the only system that solves all of the many problems of the erection of a complete built-in-place structure, and will produce an economical low-cost house. It is the only system that allows for adaptability to any plan, dimension and architectural style desired. This is quite remarkable, considering the many thousands of different plans, with openings of various sizes, intermediate floors of all sizes and requirements, roofs of various pitches and sizes, etc. All this is accomplished with a simple basic architectural form forming a basic module employed in the system of the present invention. The system of the present invention also accommodates window and door openings, electrical work, plumbing work, and other service lines. When the walls are cast, for example, they are complete, with all the window and door frames in, the electrical wiring in, plumbing conduits in, and the wall is finished on both surfaces. In addition to the form used in the system of the present invention, specially developed hardware and accessory items have been developed to accomplish a rapid, simple erection of the forms. These items of hardware and accessory as described hereinafter are an integral part of the success of the subject system.

A majority of the people in the world today live in countries where masonry construction is essential. It is highly significant that there is no system in use today that will produce masonry housing on an industrial scale necessary to solve the critical housing problem. Without exception, these countries are still using methods employed for centuries to produce their housing. The system of the present invention will industrialize masonry construction techniques, and solve the critical housing problem for social interest construction.

SUBJECT OF THE INVENTION

It is the object of the subject invention to overcome the problems associated with prior art techniques and provide a system for building commercially acceptable, complete cast-in-place building structures; it being un-

derstood that the term building structure should not be interpreted to be limited to a residential dwelling, but may also encompass industrial buildings, apartment buildings, warehouses, and other similar enclosed structures.

It is a further object of this invention to provide a system for building a complete, cast-in-place masonry building structure, including the foundation, exterior and interior walls, and roof structure.

10 It is still a further object of this invention to provide a system of making a cast-in-place masonry building structure, which system produces an economical low-cost house, and is adaptable to mass production techniques.

15 Another object of this invention is to provide a system for making a cast-in-place building structure that allows for adaptability to any plan, dimension, and architectural style and design, including window and door openings of various sizes, multi-story building structures, intermediate floors of all sizes and requirements, a roof of various pitch, size and overhang structure, and including electrical and plumbing conduits embedded in the cast-in-place masonry wall structure.

20 25 Similarly, it is an object of the invention to provide a system for making a cast-in-place masonry building structure which may be readily constructed using unskilled labor.

It is an associated object of the invention to provide a 30 system for making a cast-in-place masonry building structure, having attractive and acceptable interior and exterior surfaces which do not require further finishing operations or processes, other than painting if desired.

35 Another object of the invention is to provide a system of making a cast-in-place masonry building structure which does not require the use of heavy construction equipment, in that all of the forms and hardware used in the system may be easily handled by a single laborer.

40 45 A further object of the invention is to provide a system of making a cast-in-place masonry building structure in a minimum of time, and with a minimum amount of materials in order to insure an attractive and structurally sound building.

These and other objects and advantages are realized by the system of the present invention which employs a plurality of small (ranging from 2 x 2 inches through 24 x 24 inches) architectural forms, along with associated 50 specifically developed hardware for temporarily securing the architectural forms together to define the foundation, wall and roof forms into which moist concrete material is cast-in-place.

More particularly, first the site on which the building 55 is to be constructed is prepared by levelling and compacting, along with the temporary interconnection of an array of architectural forms (of a size which is easily handled by a single laborer) to define the foundation form. The various service lines such as plumbing, elec-

60 65 tricity and gas are positioned within the foundation form, as well as the requisite structural reinforcing bars which extend within the plane of the foundation and the upstanding reinforcing bars which will subsequently be embedded within the wall structure. Moist concrete is then poured into the foundation form and allowed to cure. In like manner a group of architectural forms are temporarily secured together to define two spaced wall

forms, including both interior and exterior walls, and including suitable openings for holding frames for windows and doors. The spaced wall forms rest on the slab of the foundation, and are held in spaced relationship by a plurality of wall tie members extending between said wall forms. The wall forms are constructed, and are interconnected, such that both sides of the resulting masonry walls are architecturally acceptable, without unsightly joint lines or concrete imperfections. As in the case of the foundation, the various service lines are positioned between the wall forms prior to the pouring of moist concrete. After the masonry walls have cured, the architectural wall forms are removed, and a temporary arrangement of shoring members, designed for the system of the present invention, is placed within the building structure. If desired, specially designed roof-supporting brackets are secured to the wall ties on the exterior of the building for supporting overhanging portions of the roof form. The latter is constructed by temporarily interconnecting a series of architectural forms, and is supported by the shoring arrangement and the roof supporting brackets. Similar to the previous steps, moist concrete is poured in the roof form and allowed to cure, after which the roof form, temporary shoring arrangement, and the roof supporting brackets are removed. At this time, the masonry building is structurally complete. Various ancillary items such as the windows, doors, and service fixtures are then installed in the structure thereby completing the construction of the building. The resulting monolithic masonry building structure made according to the system of the present invention is structurally sound, attractive, economical to manufacture, and adaptable to mass production techniques by unskilled labor.

BRIEF DESCRIPTION OF THE DRAWINGS

FIG. 1 is a partial perspective view of two architectural forms used in the system of the present invention, and shows the inside surfaces of the forms;

FIG. 2 is a perspective, partial sectional view of the foundation of the house made according to the system of the present invention, and shows the array of architectural forms used for defining the foundation;

FIG. 2A is a sectional view taken along line 2A—2A in FIG. 2;

FIG. 3 is a perspective view, partially in section, of the interior and exterior walls of the house made according to the system of the present invention, and shows the groups of architectural forms which are temporarily secured together to define the arrangement of two spaced wall forms;

FIGS. 3A through 3K are detailed views of the various pieces of specially developed hardware used in the system of the present invention;

FIG. 4 is an exploded perspective view of a portion of the groups of architectural forms which are temporarily secured together to define the wall forms for use in the system of the present invention;

FIG. 5 is a plan view of the outside portions of a group of architectural forms which are temporarily secured together to define one of the two spaced wall forms for use in the system of the present invention, and shows the openings in the wall form for a window and a door;

FIG. 5A is a sectional view taken along line 5A—5A in FIG. 5 and includes the interior wall forms;

FIG. 6 is a perspective view, partially in section, of a roof form for use in the system of the invention;

FIGS. 6A through 6H are detailed views of various pieces of specially developed hardware used in the system of the present invention;

FIGS. 7, 8, and 9 illustrate in sequence a modified embodiment of the system of the present invention in which a two-story building structure is formed; and

FIG. 9A is a detailed view of a specially developed roof bracket used in the system of the present invention.

DESCRIPTION OF THE PREFERRED EMBODIMENTS

Before describing the several embodiments of the subject invention, it should be noted that although the detailed description will refer to the building structure as a house, any other type of enclosure having a foundation, walls and a roof may be made according to the teaching of the invention. Accordingly, it is contemplated that building structures such as industrial buildings, warehouses, apartment houses, hospitals, and the like are included within the scope of the invention.

FIG. 1 illustrates two architectural forms 10 and 10a which are of the type which may be used in the system of the present invention. Forms 10 and 10a form the subject matter of U.S. Pat. No. 3,307,822 entitled "CONCRETE WALL CONSTRUCTION FORM", which issued on May 7, 1967, to the inventor of the subject application, Robert K. Stout. Although the invention will be described with respect to the architectural forms 10 and 10a, it is readily apparent that any type of masonry form capable of producing an architectural masonry structure may also be employed. Along these lines, it should be noted that the use of forms as disclosed in the above-identified patent, as well as other concrete forms, has been extremely limited in that, heretofore, the construction industry has lacked a system for building a complete structure. Hence, such forms have been primarily employed for building walls, fences and the like, after which conventional processes were employed for completing the structure. The system of the present invention is the first system to employ the forms to completely construct a building structure.

Each architectural form, 10 and 10a, is preferably constructed of cast aluminum, but magnesium or other lightweight metal or plastic can be used. These forms are preferably made in a wide variety of sections (square or rectangular) ranging from 2 x 2 inches to 24 x 24 inches, so as to facilitate handling by a laborer, and to allow for adaptability of the present system to any desired plan, dimension and architectural style of the resulting monolithic building structure. Of course, larger architectural forms may also be used when warranted in light of the resulting building structure.

Each architectural form comprises a relatively thin sheet 12 of metal which has the overall dimensions of the desired form. Sheet 12 includes an outside surface 14 and an inside surface 16. A flange 18 on the perimeter of sheet 12 extends outwardly from the inside surface 16 of sheet 12 and protrudes beyond the outside surface 14 at a right angle thereto. A plurality of slot indentations 20 are imposed on the outside surface of flange 18 and these slot indentations are perpendicu-

larly disposed with respect to the plane of sheet 12. Holes 22 can extend through flange 18 in each one of the slot indentations 20 for a reason to be seen hereafter.

Reinforcing bar members 24 (see FIG. 2) project from the outside surface 14 of metal sheet 12 and have a thickness substantially equal to the width of flange 18, which extends around the periphery of sheet 12. The function of the bar members 24 is to reinforce metal sheet 12 and this reinforcement could obviously assume several different patterns.

The inside surfaces of forms 10 and 10a are substantially identical, and comprises an architectural brick arrangement formed by a plurality of elongated narrow bars 30 horizontally extending across the inside surface 16, and a plurality of non-continuous vertical bars 32 on the same surface to complete the brick pattern. It should be noted that the vertical bars 32' adjacent the side edges of surface 16 have a width equal to only half that of the vertical bars 32. Similarly the bars 30' at the top and bottom of surface 16 are half the width of the horizontal bars 30. It should also be noted that the bars 32 have been alternatively discontinued. The area of the inside surface 16 between the bars 30 and 32 is shown to be rough and irregular, and is comprised of a plurality of small arcuate indentations and protruding portions of different sizes located in an irregular and non-symmetrical pattern. By this arrangement, as shown in FIG. 1, the adjacent side edges of the forms 10 and 10a match and register with each other to better hide any seam between adjacent forms. Furthermore, the indentations and protruding portions are substantially arcuate in shape to avoid any sharp lines or edges. It is preferred that the vertical side edges of each form be identical so that when a plurality of such forms are aligned in side by side abutting relation, the adjacent vertical side edges of the forms will register with each other. The registration of adjacent side forms insures that the resulting concrete structure provides an architectural finish which will not necessitate further finishing processes.

Also formed in the flange 18 of each architectural form are a plurality of holes 23 which are employed for securing adjacent forms together and to insure alignment of said forms. In general, the architectural forms which are employed for forming the outer periphery of a surface such as the foundation and the roof do not include the slot indentations 20. The latter are provided in an architectural form in order to accommodate a wall tie for maintaining the spacing between two spaced wall forms that are employed for forming the upstanding walls of a building structure. In addition to the slot indentations 20, such wall forms also include holes 23 for maintaining alignment and securing together adjacent architectural forms. Further details relative to the type of form used during the several steps of the subject system will be discussed hereinafter.

The first step in the system of the subject invention, as applied to the construction of a monolithic masonry house, comprises the formation of the floor or foundation. Referring to FIG. 2, the site on which the masonry house is to be constructed is first levelled, after which the ground G is compacted, and a peripheral trench 40 is dug for defining the peripheral footing of the result-

ing floor structure. In addition, interior trenches 40' may also be prepared for providing footings for the interior walls of the structure. Next, an array of architectural forms 10 are temporarily interconnected by means of suitable pin and wedge arrangements (to be described with reference to FIG. 3E hereinafter) and provided about the entire periphery of the floor area, with the array of architectural forms being fixed in place by means of stakes 42. The various service conduits, including electrical wiring (not shown) and plumbing lines 44 are placed within the confines of the floor area, as well as a network of reinforcing bars 46, the extent of which is determined by the desired structural characteristic of the resulting structure. In addition, upstanding reinforcing bars 48 are provided about the periphery of the floor structure, as well as within the interior of the floor structure corresponding to the location of the interior walls. Next, moist concrete 50 is poured and levelled within the confines of the foundation forms, and it is suggested that a V-groove 52 be provided about the periphery of the floor spaced from the form to cooperate with the upstanding walls to define a moisture joint or barrier for the resulting house structure. After the concrete has cured, the foundation forms may be removed, preparatory to the erecting of the wall forms.

The next step in the system of the present invention is the erection of the wall forms which are mounted on the concrete floor, preferably spaced within an inch or two of the outer periphery of the floor area. The architectural forms employed for forming the wall form are of the type which include the slot indentations 20 in order to receive wall ties that function to maintain the proper spacing between the interior and exterior wall forms as described hereinafter.

Basically, this step in the system of the subject invention involves the formation of a continuous arrangement of two-spaced concrete wall forms by the temporary interconnection of a group of architectural forms, with the arrangement defining the upstanding exterior and interior walls of the house. As shown in FIG. 3, the wall forms are defined by an interior group 60 of wall forms and an exterior group 62 of wall forms, with the inside surfaces 16 of the forms facing toward the area where the concrete is to be poured. As a result, the resulting wall structure, as shown at the top of FIG. 3, is architecturally finished both on the exterior surface thereof and the interior surface thereof. The arrangement of the wall forms 60 and 62 is continuous to include, besides the outer peripheral wall of the house, an interior wall, designated by numeral 64, and an extension of the house, generally designated by numeral 66. In interconnecting the various wall forms, openings are left for the windows 68 and doors, one of which is shown at 70.

FIG. 3A illustrates in detail the interconnection between two adjacent architectural panels 10 and 10a. In order to form a temporary interconnection between said panels, fastening means including a pin 76 (see detail FIG. 3E) having a slot 77 and cooperating wedge 78 (see detail FIG. 3F) are employed. Extending between the interior 60 and exterior 62 wall forms are a plurality of wall ties 74 (see detail FIG. 3G). In the interconnection of architectural panels 10 and 10a, a wall tie 74 is positioned within the aligned slot indentations 20 of the adjacent panels 10 and 10a.

tions 20 in the respective panels, after which the pin 76 is positioned within the aligned holes 22 and the hole 75 in the wall tie 74, and the wedge 78 is then positioned within the slot 77 of pin 76. The wedge is forced into slot 77 in order to form a tight interconnection between the architectural forms. Additional pins 80 are then passed through the aligned holes 23 in order to insure proper alignment between the adjacent forms. In like manner, additional pins are provided between the adjacent forms disposed above and below said panels 10 and 10a. If desired, the additional pins may be in the form of nuts and bolts.

Referring to FIG. 3B, a modified form of temporary interconnecting fastening means is illustrated for those instances wherein a smaller architectural form 10b is to be provided between forms 10 and 10a. Form 10b is generally similar to forms 10 and 10a, and includes slot indentations 20. Instead of providing two temporary fastening means of the type illustrated in FIG. 3A, resort is made to a fastener comprising an elongated pin 90 which is slotted as at 92, 92 at its opposite ends, and a pair of wedges 94 and 94 are employed. Pin 90 is long enough to extend through the two abutting slot indentations of the adjacent panels, so that a single temporary fastening means is employed for securing the three panels together. As in the structure of FIG. 3A, suitable wall ties 74 are employed, as well as aligning pins 80.

FIG. 3C illustrates in detail a device employed in the system of the present invention in order to insure the alignment of the wall forms. More particularly, a Z-shaped member 100 is provided with suitable apertures for cooperating with the rib reinforcing portions 24 of the architectural forms so as to define a bracket for holding a straight-edge, such as a 4 x 4 inch wood member. As illustrated in FIG. 3, a plurality of U-shaped members 100 are fixed to the upper panels on the exterior wall form 62, and a straight-edge 102 is slipped into the members 100, and is effective to maintain the alignment of the wall member during the concrete pouring operation. A similar arrangement may be provided on the interior wall form 60. The U-shaped member may be secured to the architectural forms by temporary fastening means of the type illustrated in FIG. 3A. Alternatively, the U-shaped members may be secured to the architectural forms by a quick clamp 104 of the type illustrated in FIG. 3I. The quick clamp 104 comprises a U-shaped member having an upstanding pin 106 for passage through the associated form, with one leg 108 of the quick clamp 104 being inclined relative to the other leg 110 whereby, after the pin 106 is inserted through a hole in the form, the quick clamp is rotated about the pin 106 and the relative incline between surfaces 108 and 110 results in a wedging action thereby securely holding the abutting form members together. The quick clamp 106 may also be employed for maintaining adjacent architectural forms together.

Referring again to FIG. 3, it is noted that the wall form for the interior wall 64 is additionally connected to the wall form 60 by means of corner braces 114. As shown in detail in FIG. 3D, each corner brace 114 includes a turnbuckle 116 terminating in opposed pins 118 which are adapted to fit within the holes 23 in adjacent architectural forms.

In order to facilitate the ease of erection of a building structure or house made according to the system of the present invention, the window frames and door jambs are temporarily connected to the wall forms for use as part of the form structure preparatory to the pouring of concrete. The window and door frames are held to the architectural forms by means of specially designed whaler clamps, designated by the numeral 120, one of which is illustrated in detail in FIG. 3H. The whaler clamp 120 is generally U-shaped in configuration, and includes a pin 122 adapted to fit within a hole 23 in the associated architectural form. The opposite leg portion of the whaler clamp is inclined so as to frictionally grip the opposite architectural form. After the wall structure has been formed, the whaler clamps are removed, but the window and door frames remain in place for easy attachment to the door and window structures, respectfully. Whaler clamps are also employed for securing the end plate to the form for the interior wall 64.

FIG. 3J illustrates a scaffold bracket 130 which may be secured to the wall forms 60, 62 for providing support for scaffold 132. The scaffold bracket 130 includes a U-shaped edge portion 134 which attaches to one of the architectural forms, with the lower end 136 of the scaffold bracket 130 resting against a lower portion of the form.

FIG. 4 illustrates an exploded view of the various architectural forms which are temporarily assembled in order to form the interior and exterior wall forms 60 and 62. As clearly illustrated in FIG. 4, the architecturally finished or inside surfaces 16 of the forms are in facing relationship whereby both the interior and exterior surfaces of the resulting wall structure are architecturally finished, and do not require additional finishing processes. FIG. 4 also illustrates an exterior angle bracket 140 which is employed at the junction of the exterior wall forms 62. Angle bracket 140 is provided with a plurality of holes 142 corresponding to the holes 22 and 23 in the adjacent architectural forms. In addition, FIG. 4 illustrates the various different sized architectural forms which may be employed for forming the wall forms 60, 62.

45 FIGS. 5 and 5A illustrate an assembled wall form, including openings for a door and window. The arrangement of the architectural forms as shown in FIGS. 3-5 provides a continuous arrangement of two-spaced
50 concrete wall forms which are formed by the temporary interconnection of a plurality of architectural forms. The arrangement defines the upstanding exterior and interior walls of the house, with spaced walls being interconnected by a plurality of wall ties. Since the wall
55 forms are formed by interconnecting a plurality of relatively small architectural forms, it is readily apparent that heavy construction equipment is not required to reach this stage of the system of the present invention, nor is it required in order to complete the masonry
60 building structure. In addition, the use of the pin and wedge arrangements illustrated in FIGS. 3A and 3B, as well as the quick clamp device of FIG. 3I greatly facilitates the erection of the wall forms, as well as
65 facilitating the removal of the wall forms upon completion of the formation of the walls.

Moist or uncured concrete is poured in the space defined between the two-spaced concrete wall forms.

60 and 62, and allowed to cure. The concrete may be poured to a point level with the upper edge of the wall forms, in which case a flat roof would be obtained, or alternatively, the uncured concrete may be poured and finished in a manner so as to be inclined from one end of the house to the other, in which case an inclined roof structure may then be constructed. After the monolithic concrete walls have been poured, the architectural forms are removed, and the wall ties 74 may also be removed, with the resulting holes left by the wall ties being filled with a suitable caulking compound. FIG. 3K illustrates an alternate form of wall tie wherein the tie 134 is tapered both in width and along its length thereby enabling its easy removal from the cured concrete wall. It should be understood that certain of the wall ties may be maintained in place and employed during the construction of the roof structure during the final step of the system of the present invention. Also, the wall ties may be constructed to include lines of weakened areas so that those portions of the tie extending beyond the resulting wall may be readily snapped off, thereby leaving the bulk of the tie within the wall for structural purposes.

In order to complete the construction of a monolithic masonry house, the step of forming a concrete roof on the masonry structure mentioned hereinabove will now be described in detail, with particular reference to FIG. 6. First, a temporary arrangement of shoring members is constructed within the enclosure defined by the exterior walls. This may be accomplished through the use of a plurality of jacks 150, one of which is shown in detail in FIG. 6A. Jack 150 is of the variable length type, and its upper end is suitably configured to accept a jack head 152, shown in detail in FIG. 6B. The upper end of the jack head 152 includes a U-shape member having a pair of aligned holes 152', and a pivot top 154 (See FIG. 6C) is pivotally connected, by a suitable pin means, to the upper end of the jack head 152. Pivot top 154 comprises a generally elongated U-shape member designed to accommodate an elongated structural beam member 156. As shown in FIG. 6, a plurality of jacks are aligned along two walls of the structure, with each aligned arrangement of jacks accommodating two parallel structural beam members 156. Extending between and transverse to the longitudinal axis of the generally parallel structural beam members 156 are a plurality of telescoping support beams 160. As shown in detail in FIG. 6D, each telescoping beam 160 includes on the opposite ends thereof flanges 162 adapted to rest on the respective beams 156, 156. The combination of the jacks, the structural members 156, and the arrangement of telescoping beams 160 provides a temporary structure for supporting a plurality of interconnected architectural forms 10. The latter are shown in FIG. 6 as being of the smooth type, whereby the interior surface of the resulting roof will be smooth.

In order to extend the roof structure beyond the perimeter of the house as defined by the exterior walls, resort is made to overhanging braces of the types illustrated in FIGS. 6E and 6F. The overhang brace illustrated in FIG. 6E is of the variable angle type, and is generally designated by numeral 170, and includes a support leg 172 which includes apertures for connection to wall ties extending in the wall portion of the masonry wall. Secured to the upper end of the support

leg 172 is a fixed arm 174, having pivotally connected at its outer end thereof a second arm 176. Arm 176 may be inclined relative to fixed arm 174 by means of a threaded screw arrangement 178, whereby the variable angle overhang brace 170 may be adjusted to any desired pitch of the roof.

FIG. 6F illustrates a second form of overhang brace which is of the fixed type, and is designated by numeral 180. Fixed overhang brace 180 comprises a support leg 182, to which is fixed an arm 184 disposed at a right angle to the leg 182, and an angle support leg 186. As shown in FIG. 6, in the construction of a house according to the system of the present invention wherein an inclined roof is provided, overhang braces 180 of the fixed type illustrated in FIG. 6F would be used along the left side of the house, while variable angle overhang braces 170 would be employed along the front edge, or pitched surface of the roof.

The edge of the roof form is defined by means of roof edge supports illustrated in FIGS. 6G and 6H. The roof edge supports are secured to the flanges of the architectural forms disposed about the periphery of the roof form. Roof edge support 190 illustrated in FIG. 6G provides an arrangement wherein the upstanding surface 200 of the roof form is mounted flush with the architectural roof form, whereas roof support bracket 192 illustrated in FIG. 6H includes a stepped portion, which enables the upstanding surface 200 to be stepped in with respect to the edge of the roof.

As is clearly shown in FIG. 6, where an inclined or pitched roof is desired, the roof form is supported by the temporary arrangement of shoring members within the enclosure, and by the various overhang braces in a manner whereby a portion of the upstanding wall projects above the plane of the architectural roof forms. By this arrangement, after the uncured concrete is poured to form the roof structure, a monolithic connection between the walls and the roof of the resulting house is achieved. After the roof form has been completed, uncured concrete is poured into the confines of the roof form and allowed to cure. The temporary arrangement of shoring members is then removed, thereby completing construction of the house according to the system of the present invention.

FIGS. 7-9 illustrate a system for constructing a two-story house. The steps involved in forming the foundation or floor and the walls, as well as the roof as described with reference to FIGS. 1-6 are identical, except that, as shown in FIG. 7, the uppermost architectural form 10 is left in place and is employed during the formation of the second floor as the outer peripheral edge thereof. After the upper floor has cured, the wall forms for forming the second story of the building structure are assembled, as shown in FIG. 8. It is suggested that a bracing member 202 be provided at this time preparatory to the formation of the walls of the second story. Also, to facilitate construction, resort is made to the scaffold braces of the type illustrated in FIG. 3J for enabling the workmen to assemble the temporary wall forms for the second story. After the concrete for the walls of the second story has been poured and cured, the roof is constructed in a generally similar manner to that illustrated with reference to FIG. 6. This is shown in FIG. 9, with FIG. 9A illustrating in detail the variable angle overhang brace used for supporting the roof form.

Accordingly, the present invention provides a system for making a commercial acceptable built-in-place building structure of concrete. The system of the present invention produces a finished result on both surfaces of the wall. This is due to the pattern which is an integral part of the architectural form. This feature is essential, as no further finishing is required on the wall surface. This is necessary to the overall economy of cast-in-place concrete structures. The architectural forms employed in the present system go together like a giant erector set, with a simple pin and wedge fastener. This results in very significant savings in labor costs. There is no other forming system which can produce an architectural result in concrete at anything approaching the speed of the system of the present invention. The present system is so simple that unskilled men can accomplish the same results as skilled brick layers and other craftsmen. Since the architectural forms are made of light-weight material, large enough sections can be handled by one man to be very efficient and rapid, and no expensive machinery is required. The system of the present invention is the only forming system which is completely designed to produce a cast-in-place house or other structures. An architectural result in the concrete is absolutely essential to an acceptable cast-in-place concrete house. In many areas of the world, special climatic conditions require special techniques and methods of construction. Therefore, people have rejected the cast-in-place concrete house, not only for an attractive appearance, but because they consider concrete to be cold, or that it retains heat, etc. The system of the present invention is a complete system which has taken this into consideration and it has solved these problems. One innovative method of providing comfort and insulated properties to the concrete, is by incorporating special chemicals in the concrete which produce dead air spaces which provide insulation properties. In addition, the system of the present invention may be employed for the construction of multi-story buildings, and allows for adaptability to any plan, dimension, and architectural style design. While the invention has been described in connection with several preferred procedures, it will be understood that it is not intended to limit the invention to those procedures. On the contrary, it is intended to cover all alternatives, modifications and equivalents as may be included within the spirit and scope of the invention as defined by the appended claims.

What is claimed is:

1. A method for making a cast-in-place concrete structure comprising the separate and sequential steps of:
  - a. levelling the ground area on which the concrete structure is to be constructed and forming a foundation form by temporarily interconnecting a plurality of architectural forms to define the area of the foundation;
  - b. forming the foundation and floor of the concrete structure by pouring uncured concrete into the confines of said foundation form and allowing said concrete to cure;
  - c. removing said foundation form;
  - d. forming a continuous arrangement of two-spaced concrete wall forms by temporarily interconnecting a plurality of architectural forms, said two-spaced concrete wall forms being interconnected

by a plurality of upper and lower wall form ties, said arrangement of wall forms defining the upstanding exterior and interior walls of the said concrete structure;

- e. forming the upstanding exterior and interior walls of the concrete structure by pouring uncured concrete into the space defined between said two-spaced concrete wall forms, and allowing said concrete to cure;
  - f. removing said spaced concrete wall forms;
  - g. removing said lower wall form ties and leaving the upper wall form ties for subsequently supporting brackets for the roof form;
  - h. constructing the roof form portion of the concrete structure by,
    - i. providing a temporary arrangement of shoring members within the enclosure defined by said exterior walls;
    - ii. securing outwardly overhanging brackets to said upper wall form ties externally of the exterior walls in order to provide a temporary support for a roof form; and
    - iii. forming a roof form by temporarily inter-connecting a plurality of architectural forms, and supporting said roof form on said arrangement of shoring members and said brackets, with the peripheral edge of said roof form being defined by a continuous upstanding member;
  - i. forming the roof of the concrete structure by pouring uncured concrete into the confines of said roof form and allowing said concrete to cure; and
  - j. removing said temporary arrangement of shoring members, brackets, upper wall form ties, and said roof form.
2. A method for making a cast-in-place concrete structure as in claim 1 wherein the step in forming the upstanding exterior and interior walls of the concrete structure includes placing and curing uncured concrete in the two-spaced concrete forms at an inclined angle from one end of the structure to the opposite end thereof in order to enable the roof to be formed at a desired pitch.
  3. A method for making a cast-in-place concrete structure as in claim 1 wherein the step of forming a continuous arrangement of two-spaced concrete wall forms comprises constructing the wall forms to include openings for receiving the frames of doors and windows in the concrete structure, with the periphery of said openings being closed by cooperation of the wall forms and the window and door frames, said window and door frames being temporarily secured to the wall forms by whaler brackets.
  4. A method for making a cast-in-place concrete structure as in claim 1 including the additional step of securing straightening members to the two-spaced concrete wall forms prior to the pouring of moist concrete material therein.
  5. A method for making a multi-store cast-in-place concrete structure comprising the separate and sequential steps of:
    - a. levelling the ground area on which the concrete structure is to be constructed and forming a foundation form by temporarily interconnecting a plurality of architectural forms to define the area of the foundation;

- b. forming the foundation and floor by pouring uncured concrete into the confines of said foundation form and allowing said concrete to cure;
- c. removing said foundation form;
- d. forming a first continuous arrangement of two-spaced concrete walls by temporarily interconnecting a plurality of architectural forms, said first concrete wall forms being interconnected by a plurality of upper and lower wall form ties and defining the upstanding exterior and interior walls of the first story of said concrete structure;
- e. forming the upstanding exterior and interior walls of the first story of the concrete structure by pouring uncured concrete into the space defined between said first concrete wall forms, and allowing said concrete to cure; 15
- f. removing said first concrete wall forms except for maintaining a series of architectural forms connected to said upper wall form ties externally of the exterior walls of the first floor; 20
- g. constructing the first floor form of the concrete structure by,
  - i. providing a temporary arrangement of shoring members within the enclosure defined by the first story exterior walls; and
  - ii. forming a floor form by temporarily interconnecting a plurality of architectural forms, and supporting said floor form on said arrangement of shoring members;
- h. forming the first floor by pouring uncured concrete into the confines of said floor form and allowing said concrete to cure; 30
- i. removing said temporary arrangement of shoring members and said floor form; along with the series of architectural forms defining the peripheral edge of said first floor; 35
- j. forming a second continuous arrangement of two-spaced concrete wall forms, said second arrangement of wall forms being mounted on said first floor, said second concrete wall forms being interconnected by a plurality of upper and lower wall form ties, and defining the upstanding exterior and interior walls of the second story of said concrete structure; 40
- k. forming the walls of the second story of the structure by pouring uncured concrete into the space defined by said second concrete wall forms and allowing said concrete to cure; 45

- l. removing said second concrete wall forms;
  - m. removing the lower wall form ties in the walls of the second story and leaving the upper wall form ties for subsequently supporting brackets for the roof form;
  - n. constructing the roof form of the two-story concrete structure by,
    - i. providing a temporary arrangement of shoring members within the enclosure defined by the exterior walls of the second story, and supported on said first floor;
    - ii. securing overhang brackets to the upper wall form ties externally of the exterior walls of said second story in order to provide a temporary support for a roof form to enable the latter to extend beyond the peripheral edges of said upstanding exterior walls of said second story; and
    - iii. forming a roof form by temporarily interconnecting a plurality of architectural forms, and supporting said roof form on said arrangement of shoring members and said overhang brackets, with the peripheral edge of said roof form being defined by a continuous upstanding member;
  - o. forming the roof of the multi-story concrete structure by pouring uncured concrete into confines of said roof form and allowing said concrete to cure; and
  - p. removing the first and second continuous arrangement of concrete wall forms, the temporary arrangement of the shoring members, the upper wall ties, the overhang brackets, and said roof form.
6. A method for making a cast-in-place concrete structure as in claim 5 wherein in the steps in forming the continuous arrangement of two-spaced concrete wall forms for the first and second story walls, leaving openings for receiving the frames of doors and windows in the concrete structure, with the periphery of said openings being closed by cooperation of the wall forms and the window and door frames, said window and door frames being temporarily secured to the wall forms by whaler brackets.
7. A method for making a multi-story cast-in-place concrete structure as in claim 5 comprising the further steps of repeating steps (f) through (m) prior to the steps of constructing the roof form and forming the roof of the concrete structure in order to form additional stories for the concrete structure.
